UNITED STATES PATENT OFFICE

EDWARD C. BRYANT, OF ATLANTA, GEORGIA

RAZOR BLADE SHARPENER

Application filed February 16, 1931. Serial No. 516,169.

This invention relates to sharpening devices for razor blades and like edged tools, and is especially adapted for sharpening the double edged blades of safety razors.

5 An object of the invention is the provision of a blade sharpener, by means of which the microscopic teeth along the cutting edge of the blade may be relined to restore said edge together with hand gripping and support 55 engaging means so that the device may be either held in the hand while in use or securely attached to a support.

Another object of the invention is the provision of a blade sharpener which is simple 15 and economical in construction, and reliable and efficient in use.

With the above and other objects in view, the invention further includes the following 20 novel features and details of construction, to be hereinafter more fully described, illustrated in the accompanying drawing and pointed out in the appended claim.

In the drawing:—

Figure 1 is a perspective view of a razor 25 blade sharpener constructed in accordance with the invention.

Figure 2 is a transverse sectional view of the same.

Referring to the drawing in detail where- 30 in like characters of reference denote corre- 35 sponding parts, the reference character 10 indicates the body of the device which is arcuate in cross section and provides an upper convex sharpening surface 11. The body is 40 made of glass or some other non-abrasive material and has integrally formed therewith spaced outwardly curved, longitudinally ex- 45 tending flanges 12. These flanges are con- 50 caved along their outer surfaces as indicated 55 at 13 and provide finger gripping flanges 60 whereby the device may be conveniently held 65 in the hand for use.

The flanges 13 are spaced apart to provide 70 a slot or channel 14, the inner portions of 75 the opposed side walls of which are parallel 80 as indicated at 15. These parallel portions 85 provide gripping means for engagement over 90 the edge of a drawer or like member as indicated in dotted lines at 16 in Figure 2. The 95 remaining portions of these walls are out-

wardly curved as shown at 17 so as to provide guides when attaching the device to the drawer or other supporting member 16.

In use, the sharpener may be either held in the hand of the user, or it may be attached as 55 shown in Figure 2, while if desired, the sharpener may rest upon a broad flat surface, the flanges 12 having their lower edges disposed in the same plane.

By placing a blade upon the concaved sur- 60 face 11 and exerting a slight pressure thereon while reciprocating the blade in the direction of the curve, the microscopic teeth along the edges of the blade will be forced inward. The blade is then reversed and the action re- 65 peated, at the expiration of which all of the microscopic teeth which have become dis- 70 aligned through the use of the blade, will be realigned so that the cutting surface will be restored.

The invention is susceptible of various 75 changes in its form, proportions and minor 80 details of construction and the right is herein reserved to make such changes as properly fall within the scope of the appended claims.

Having described the invention what is 85 claimed is:—

In a razor blade sharpener, including a 90 body having an outer honing surface, a pair 95 of spaced reversely curved finger gripping flanges extending from the body having straight alining ends to afford a support for the body when arranged on the smooth sur- 100 face, said flanges defining a slot therebetween and the opposed parallel walls at the inner end of the slot to define a gripping portion, and outwardly curved guide walls at the outer portion of the slot, for guiding a vertical support between said flanges and into grip- 105 ping engagement with the parallel inner walls thereof.

In testimony whereof I affix my signature.

EDWARD C. BRYANT,
